UNITED STATES PATENT OFFICE.

IRA CUNNINGHAM AND ROY W. WAY, OF COVINGTON, OKLAHOMA.

EXPLOSION ENGINE.

Application filed March 15, 1920. Serial No. 365,794.

To all whom it may concern:

Be it known that we, IRA CUNNINGHAM and Roy W. WAY, citizens of the United States, residing at Covington, in the county 5 of Garfield and State of Oklahoma, have invented a new and useful Explosion Engine, of which the following is a specification.

This invention has reference to explosion 10 or internal combustion engines particularly of the two cycle V type, though not necessarily confined to such particular type. Moreover, the invention is adapted to an engine designed to run at high speeds, al- 15 though it may in whole or in part be used for relatively low speed engines.

The invention is such that it is adapted to engines for various purposes with but few changes of minor character, the principle of 20 the invention being retained irrespective of the work to be done.

In accordance with the invention, the charge to the cylinders, the engine being of the multi-cylinder type, is under the control 25 of pumps, one for each pair of cylinders, with the pumps and cylinders so related that despite the two cycle arrangement, each cylinder is thoroughly scavenged by the fresh charge even though the pistons be moving at 30 a high rate of speed. It is important, in order to get economical and powerful action, that the burnt or dead gases be forcibly and completely expelled by the incoming charge. This is mechanically done like the four cycle 35 type of engine and is performed by the pump. Since each pump controls the charge to two cylinders, the capacity of the pump is made sufficient for the purpose, and because of the thorough explosion of the burnt 40 gases, each cylinder gets a full charge of fresh gases, therein differing from the ordinary type of two cycle engines.

In carrying out the invention and consider- 45 ing only the action of one pump and two related cylinders, the pistons of the pump and cylinders are so positioned with respect to each other, that the exhaust ports of the power cylinders are opened a short interval before the fresh charge already partially 50 compressed by the pump is allowed to pass into the power cylinder, whereupon the fresh charge under compression is directed toward the head of the cylinder to return toward the exhaust ports, which latter pro- 55 gressively open due to the power stroke of the power pistons. The pump completes its

compression stroke while the piston of the power cylinder is returning on the compres- 60 sion stroke, and because of the lead of the pump piston the final movement of the power piston compresses the power charge to the full degree of compression desired. While this final compression is occurring, the pump is on the intake stroke and ultimately passes to the compression stroke, so 65 that when the charge is forced into the power cylinder it has the requisite compres- sion imparted to it.

The invention also contemplates the use of a valve structure in the pump whereby 70 losses which heretofore have occurred in two cycle engines during the compression of the charge, are avoided.

The invention will be best understood from a consideration of the following detailed de- 75 scription taken in connection with the accom- panying drawings forming part of this specifi- cation, with the understanding, however, that the invention is not confined to any strict conformity with the showing in the 80 drawings, but may be changed and modified so long as such changes and modifications mark no material departure from the salient features of the invention as expressed in the 85 appended claims.

In the drawings,

Fig. 1 is a view partly in side elevation and partly in vertical section of an explo- 90 sion engine embodying the invention.

Fig. 2 is an irregular cross section through the machine, the section cutting a power cyl- 95 inder on one side of the upright central plane and a pump on the opposite side thereof.

Fig. 3 is a top plan view of the power cyl- 95 inders and pumps on one side of the engine, omitting some parts.

Fig. 4 is a horizontal section through the structure shown in Fig. 3 on the plane of the intake and exhaust valves of the power cyl- 100 inders.

Fig. 5 is a diagram showing the arrange- 105 ment of the crank centers in different posi- tions.

Fig. 6 is a plan and edge view of a feather valve plate used in connection with the pumps.

Fig. 7 is a plan and cross section of a valve holding member associated with the 110 valve plate of a pump.

Fig. 8 shows plan and edge views of valve strips.

Referring to the drawings, there is shown a crank case 1 in which is journaled a crank shaft 2 having end journal bearings 3 and an intermediate journal bearing 4. In the particular showing of the drawings, the crank shaft is provided with six wrist pins 5, although it is to be understood that any other appropriate number of wrist pins may be employed depending upon the size of the engine and the number of power units of which the engine is composed. In Fig. 1, there are shown one half of the total number of power units, each composed of two power cylinders 6, each carrying a piston 7 connected by a pitman 8 to one of the wrist pins 5. The showing of the drawings is that of an 8-cylinder two-cycle internal combustion engine of the V type of disposition of the cylinders, although it is to be understood that while there are certain advantages in such arrangement, the invention is by no means limited thereto. The charges for the cylinders are delivered thereto by means of pumps, each pump 9 supplying two cylinders 6, and each pair of cylinders and the pump belonging to it are, for convenience and economy of construction, cast en bloc, wherefore an 8-cylinder engine, in the construction shown in the drawings, comprises four groups each consisting of two cylinders and a pump, with two groups on one side of the longitudinal center plane of the engine and two groups on the other side thereof. Each pump 9 is provided with a pump piston 10 and a pitman 11. The several pitmen are connected to respective wrist pins 5 so that a pitman 11 on one side of the central plane of the machine is connected to the same wrist pin 5 as the corresponding pitman on the other side of the machine. In order to provide for such an arrangement, one pitman connected to a wrist pin 5 has a head 12 bifurcated to straddle the head 13 of the opposed pitman, wherefore the pistons 7 of the corresponding opposed cylinders work in unison. Similarly, a pitman 11 of a pump on one side of the longitudinal central plane of the engine has a bifurcated head 14 engaging the corresponding wrist pin 5 while the pitman 11 of the opposite pump has a head 15 engaging the same wrist pin 5.

Each piston 7 has a curved deflector 16 on its head and projecting into the explosion chamber 17 of the cylinder, while the end of the explosion chamber 17 toward which the deflector 16 is directed has a concaved wall 18, see Fig. 2, after the usual two-cycle engine practice. At an appropriate position with respect to the length of the power cylinder there is provided an exhaust port 19, usually but not necessarily in the form of a plurality of openings, while on the other side of the cylinder is an inlet

port 20. The arrangement is such that on the power stroke of the power piston the exhaust port 19 is opened a small fraction of time prior to the opening of the inlet port.

Cast in one piece with the pump and power cylinders of a unit is a passageway 21 communicating with the intake ports 20 and with the outer end of the pump cylinder 9, the passageway 21 connecting to both power cylinders directly and by a branch 22 to the interior of the pump cylinder 9, the passageway 21 and the branch 22 forming an intake manifold which embraces one side of the power and pump cylinder unit. Seated in the branch 22 is a screen 23, shown in Fig. 2, and this screen is held in place and rendered easily accessible by a cover plate 24 secured by screws or bolts 25.

The passageway 21 is individual to a unit and forms the means by which a charge compressed by the pump 9 is forced into both power cylinders of the same unit at the same time. The exhaust ports 19 communicate with an exhaust duct 26 which may be secured by bolts or screws 27 or in other manner to both units on either side of the engine where the engine is a multi-unit engine as shown in the drawings.

Each power cylinder 6 is provided with a water jacket 28, which may follow the usual practice, and a spark plug 29, and the piston 7 is furnished with the usual packing rings 30 and 31, while a pitman 8 is connected to the piston 7 by the customary wrist pin 32 which may intersect a lubricating groove 33, these several features being common to gas engines.

The pump piston 10 is provided with packing rings 34, a wrist pin 35 and lubricant groove 36 similar to those provided for the power pistons, except that the packing rings 34 may be of a different character from the rings 30, since they do not have to withstand great heat.

Each pump 9 is furnished with a cylinder head 37 having the inner face 38 slanting from one side toward the other to better distribute an incoming charge. The head 37 is held to the cylinder 9 by cap screws 39 or in other appropriate manner.

Through one side of the cylinder 9 close to the thinner side of the head 37 is a port 40 connected by a pipe 41 or in other appropriate manner with a source of fuel, such, for instance, as a carburetor, which latter, which may be of well known construction, is not shown in the drawings.

The end of the piston or compression chamber of the cylinder 9 is closed by a bridge-plate 42 shown installed in Fig. 2 and separately in Fig. 7. The bridge-plate 42 has a peripheral flange 43 seating in a circular channel 44 in the head of the cylinder 9 and the face of the plate or block remote

from the compression chamber of the cylinder is concaved as shown at 45. Extending through the bridge-plate or block 42 is a series of passages 46 shown as being longer than they are wide and in substantially parallel relation. Engaging the concaved face of the block 42 is a series of spring strips 47, 48 shown separately in Fig. 8. Overlying the strips 47, 48 is a feather valve plate 49 shown separately in Fig. 6. This plate has elongated passages or valve seats 50 against which the strips 47 and 48, constituting valves, engage. The plate 49 is held against the strips 47, 48 and the latter against the block or plate 42 by set screws 51 extending through the head 37 and each held against displacement by a lock nut 52.

The engine shown in the drawings comprises a plurality of units each in itself constituting a two-cycle engine composed of two power cylinders arranged on opposite sides of a pump cylinder and the three cylinders cast en bloc with the pistons of the cylinders connected to a power shaft having three cranks of which those for the two power cylinders are symmetrically arranged and that for the pump cylinder is displaced circularly to a certain extent so as to be non-symmetrical with relation to the other two cranks.

The operation of the engine may be understood from a consideration of one unit and as the two power cylinders of the unit are alike, the operation and relation of a single power cylinder and of the pump belonging to the same unit only need be considered. For this purpose, reference may be had particularly to Fig. 5, which shows a more or less diagrammatic superposition of a power cylinder upon a pump cylinder. The parts are so proportioned that when the power piston 7 on the power stroke has approached the termination of the power stroke so closely that the exhaust port 19 is partly uncovered by the power piston and the intake port 20 is about to be opened by the power piston, the crank pin 5 connected to the pitman 8 of the power piston has reached a point about forty-six degrees from the lower dead center point of the crank shaft, this position of the crank pin being shown at *a* in Fig. 5, it being assumed that the crank shaft is turning clockwise as viewed in Fig. 5. At this time the crank pin 5 connected to the pitman 8 of the pump piston 10 is in the position indicated at *b* in Fig. 5. This means that the power piston, when the intake port is about to open, is approximately forty-six degrees behind lower dead center at the position *a* in Fig. 5, and the pump piston is on the upper or compression stroke about eighty-eight degrees past bottom dead center, or one hundred and thirty-four degrees ahead of the power piston crank, as shown at *b* in Fig. 5; wherefore when the pump cylinder reaches upper dead center with its crank pin 5 at the position *c* in Fig. 5, the power cylinder will have reached forty-six degrees past lower dead center, as shown at *d* in Fig. 5, at which point the intake port is closed.

At the time that the intake port is first opened, the pump piston has traversed about half of its compression stroke so that the fresh charge is under considerable compression and during the time that the intake port is open the fresh charge is forcibly propelled through the intake port, the stream of gas striking the deflector 16 rising through the interior of the cylinder and then striking the concaved upper end of the cylinder to be returned thereby toward the exhaust port. The result is the thorough scavenging of the cylinder and when the power piston continues its return or compression stroke after closing the exhaust port there remains in the power cylinder practically nothing but an undiluted fresh charge to be compressed in the usual manner and ignited. This results in a powerful explosion similar to that obtained in a four-cycle explosion engine because of the purity of the charge, which pure charge is not obtainable in a two-cycle engine as ordinarily constructed.

Furthermore, the use of the feather valve in the charge pump is productive of a much more efficient charge than occurs in the ordinary two-cycle engine where the gases must travel to a relatively great distance from the pump to the intake of the power cylinder, the invention contemplating a very short line of travel with the inlet valve to the pump cylinder having large areas offering but little resistance to the flow of the charge into the pump cylinder.

When the pump piston is moving on the suction stroke, the valve strips or leaves 47, 48, being of spring material, readily move away from the valve plate 49 uncovering the passages or ports 50 and permitting a free flow of the gas through the passages 46 into the interior of the pump cylinder. On the return or compression stroke of the pump the valve strips 47, 48 are forced tightly against the plate 49, holding the gas in the pump from escape and compressing the charge during about half the compression stroke of the pump. At this point, the port 20 begins to open after a portion of the exploded charge has escaped through the exhaust port 19, whereupon the fresh charge under considerable pressure but not fully compressed, enters the power cylinder and expels the last remnants of the spent gases. The charge introduced into the power cylinder and in a state where it is uncontaminated by remnants of spent gases is then compressed by the compression stroke of the

power piston, the same as in a four-cycle engine. During this compression stroke of the power piston and during the power stroke, the power piston forms an effective closure 5 between the power cylinder and the pump cylinder, or more properly, between the two power cylinders and the pump cylinder, since the engine unit comprises two power cylinders fed simultaneously by one pump 10 cylinder. This closure continues during the power strokes of the power pistons and during part of the compression stroke of the pump piston and communication between the pump and the power cylinders is only 15 established after the partial and sufficiently complete exhaustion of the spent gases from the power cylinders and sufficient compression of the charge to avoid any possibility of back firing with respect to the first 20 charge when it finds admission to the power cylinders.

The invention is adapted to the construction of both high and low speed engines of the two cycle type and each unit includes 25 three cylinders, of which one is a pump cylinder and two are power cylinders. The single unit may be used alone or two units may be utilized, thus making a six-cylinder engine or four units may be disposed in V 30 relation, thus making a 12-cylinder engine and such 12-cylinder engine is particularly adapted to the V type.

What is claimed is:—

1. A two-cycle engine unit comprising 35 two power cylinders and a pump cylinder cast in one piece, and having a fuel duct leading directly from the pump cylinder to the power cylinders, said fuel duct leading downwardly and outwardly and constituting 40 an intake manifold cast integrally with and upon the communicating side only of the pump and power cylinders.

2. A two-cycle explosion engine unit comprising two power cylinders with an 45 intermediately located pump cylinder having a fuel duct leading directly from the pump cylinder to each of the power cylinders, and a water jacket, all cast in one piece, said fuel duct being located on one 50 side of the cylinder block and in contact with the water jacket.

3. A multi-cylinder explosion engine comprising a plurality of two-cycle explosion engine units, each unit being cast in 55 a single piece and having two power cylinders, an intermediate pump cylinder, a water jacket, and a fuel duct directly connecting the two power cylinders with the intermediate pump cylinder and in contact 60 with the water jacket, and means for introducing fuel charges from the fuel duct alternately into the ends of the respective power cylinders and for igniting the charges in said cylinders.

65 4. A two-cycle explosion engine unit

comprising two power cylinders and a pump cylinder for directing explosive charges into the power cylinders, a fuel passageway connecting the power cylinders and having a valved intake port, ports 70 between the passageway and respective power cylinders, a pump connected with the passageway and operable to draw successive charges thereinto and expel the same through the last-mentioned ports, 75 valves controlling the last-mentioned ports so as to alternately charge the respective cylinders, and means for exploding the charges successively after they have been introduced into the cylinders. 80

5. A two-cycle explosion engine unit comprising two power cylinders and an intermediately located pump cylinder each with a piston therein, the unit having a fuel duct leading from the pump cylinder 85 directly to each power cylinder and the pump cylinder having a capacity to supply both power cylinders simultaneously with fuel, and a crank shaft to which the pistons of the power cylinders and of the pump 90 cylinder are connected, the movements of the pump and power pistons being timed to cause a partial compression of the fuel charge by the pump cylinder while the other pistons are moving on the power 95 stroke and to continue the compression stroke during the time that the inlet ports to the power cylinders are opened by the pistons of the power cylinders.

6. A two-cycle explosion engine comprising power and fuel pump cylinders and 100 pistons therein, a pump cylinder being connected by a fuel passageway to a pair of power cylinders and cast en bloc with said power cylinders, and a crank shaft with 105 cranks to which the pistons are connected and timed in action to cause the pump piston to partially complete its compression stroke before the power pistons have completed a power stroke, and to complete its 110 compression stroke during the time the power pistons have uncovered the inlet ports to the power cylinders. 110

7. In a two-cycle explosion engine, the combination of power cylinders, each having an intake port, and a fuel cylinder pump for supplying charges of fuel to the power cylinders and provided with an inlet port and an outlet port, a passageway connecting the intake ports of the power cylinders and communicating with said outlet port of the pump, valves controlling said intake ports so as to admit charges in turn to the several cylinders upon operation of the pump, and a valve in the pump cylinder between said outlet and inlet ports. 120

8. In a two-cycle explosion engine, the combination of power cylinders each having an intake port, and a fuel cylinder 125

pump for supplying charges of fuel there- operation of the fuel pump, and a partition to, said fuel pump being provided with a extending across the pump cylinder be- head having an inclined inner surface and tween the outlet and inlet ports of the an inlet port adjacent said head, a con- pump and having an opening therethrough 15 stantly open outlet port for the pump cyl- provided with a check valve.
inder, a manifold connecting the outlet port of the pump cylinder with the intake ports of the respective power cylinders, natures.
valves controlling said intake ports of the power cylinders so as to admit charges in turn to the several power cylinders upon

In testimony that we claim the foregoing as our own, we have hereto affixed our sig- natures.

IRA CUNNINGHAM.
ROY W. WAY.
